CLAIM

The ornamental design for a fluorometer display screen with graphical user interface, as shown and described.

DESCRIPTION

FIG. 1 is a view of a first embodiment of our new design; and,

FIG. 2 is a view of a second embodiment thereof.

The outer broken line showing the fluorometer display screen is included for the purpose of illustrating environmental structure and forms no part of the claimed design. The remaining broken lines illustrate portions of the graphical user interface of the fluorometer display screen and form no part of the claimed design.

FIG. 1

The image shows a digital interface for a 'Normalization Calculator'. At the top left is a circular arrow icon. To its right, the title 'Normalization Calculator' is displayed. Below the title, the text 'Final sample molarity:' is shown, followed by two input fields: '10' and 'nmol/L'. Further down, the text 'Final sample volume:' is shown, followed by two input fields: '5' and 'μL'. At the bottom center is a large, rectangular 'Calculate' button.
